UNITED STATES PATENT OFFICE.

ELI T. ZIMMERMAN, OF MANSFIELD, OHIO.

COMBINED TOURING AND SLEEPING CAR.

1,163,056.

Specification of Letters Patent.

Patented Dec. 7, 1915.

Application filed March 12, 1915. Serial No. 13,842.

To all whom it may concern:

Be it known that I, ELI T. ZIMMERMAN, a citizen of the United States of America, residing at Mansfield, in the county of Rich-
5 land and State of Ohio, have invented cer-
tain new and useful Improvements in Com-
bined Touring and Sleeping Cars, of which
the following is a specification.

This invention relates to certain new and
10 useful improvements in combined touring
and sleeping cars, and relates more particu-
larly to automobiles.

The objects of the invention are to pro-
vide a car with reclining swiveled or rotary
15 chairs movable longitudinally of the car
either toward the front or rear thereof upon
tracks provided to prescribe certain paths
of travel for the chairs and to utilize the
20 tracks as a means of support for the chair
bases or pedestals to prevent the latter from
upsetting or tilting during the car move-
ments.

A further object of the invention is to pro-
vide an arrangement of chairs so that same
25 may be positioned about a table that is com-
mon to all of the chairs, and to mount and
relate the chairs so that adjacent chairs can
be combined to form a sleeping bed or re-
clining couch.

30 A still further object of the invention is
to provide collapsible means for forming up-
per berths or sleeping beds above the lower
beds formed by the chairs; to provide means
for storing the collapsible means when the
35 latter is not in use.

Still further the invention aims to pro-
vide a collapsible bed structure in which the
parts can be folded into minimum space.

Other and further objects of the inven-
40 tion will be later set forth and manifested
in the course of the following description.

In the drawings: Figure 1 is a side view
of the touring car body with parts broken
away to show the interior thereof with the
45 cots or beds and chairs arranged for sleep-
ing purposes; Fig. 2 is a side view showing
the interior of the touring car with the re-
clining chairs arranged in close proximity
50 to a conventional table to be used by the
passengers if they so desire, the rear end of
the body being shown in section; Fig. 3 is a

rear end elevation of Fig. 1; Fig. 4 is a de-
tail sectional view showing the method of
fastening a piece of canvas or other suitable
fabric to the frame-work for providing a
5 cot or support for the sleeper; Fig. 5 is a per-
spective view of one of the T-shaped fittings
which is used with the frame-work; and
Fig. 6 is a similar view of an L-shaped fit-
ting which is used on the ends of the frame-
work.

In proceeding in accordance with the pres-
ent invention foot plates 1 are rigidly se-
cured to the floor of the automobile and are
provided with interiorly threaded sockets in
6 which are threadedly engaged the lower ends
of standards 2. The standards are arranged
in pairs, each pair being connected by cross
braces 3 that are threadedly engaged at their
ends in fittings 3' secured adjacent the up-
per ends of the standards 2.

The end standards 2 have L-shaped upper
ends as shown in Fig. 6, and are possessed
of U-shaped seats 4 closed at their outer ends
6 by walls 5 while the intermediate standards
6 are provided with T-shaped heads 7
formed with U-shaped seats. Sections of
pipe 8 are arranged in the seats with their
adjacent ends in abutment; canvas 9 being
wrapped about the pipe sections and being
drawn taut or stretched by means of a strap
and buckle 11 so as to form a bed.

In operation when it is desired to knock-
down the berths which the canvas members
9 form, the latter are lifted out of the seats
4 and 7 then rolled up and placed in boxes
18 provided for their reception along the
sides of the car. The cross braces 3 are
then unthreaded from the fittings 3' and
the standards 2 and 6 are unthreaded from
the foot plates 1 whereupon the standards
and cross braces may be placed in the side
boxes 18 or in drawers 17 that are provided
at the front end of the car as shown in Figs.
1 and 3. Bedding may be kept in the
drawers 17 and the latter also used for other
storage purposes.

Arranged longitudinally of the car are
two pairs of spaced angle iron tracks 14
which slidably receive therein the bases 15
of chair pedestals 16. These chairs are pref-
erably of the rotary or swivel type and have

adjustable backs 13 and adjustable foot or leg rests 21 and may have arms 20, as shown in Fig. 2.

By slidably mounting the chairs same 5 may be moved to a position whereby the back 13 of a front chair when lowered will rest upon the seat of the adjacent rear chair and thus provide a cot or lower berth. The two pairs of tracks 14 are spaced so as to receive a table T in said space whereby the latter 10 may be used as shown in Fig. 2 by arranging the chairs therearound.

The rear end 19 of the automobile may be hinged as indicated at 28 so that the latter 15 may be lowered to the position shown in Fig. 1 to serve as a table, shelf, or the like. As illustrated in Fig. 3 the upper berths which the canvas members 9 provide are located above the chairs 3, an arrangement 20 which thus uses the space in the automobile to the best advantage.

What is claimed is:

1. In a car, angle iron tracks, and adjustable chairs having bases slidably engaged 25 with the tracks and movable to a position so that the head portion of a front chair can be moved down to a position to be supported upon the seat portion of a rear chair.

2. In a car, foot plates having threaded 30 sockets, standards threaded into said sockets, cross braces removably connected to the standards, the end standards having seats which open upwardly and are closed at their outer ends, the intermediate standards having 35 T-shaped heads with seats that open upwardly and are open at both ends, bars having their ends abutting and their outer ends engaged with the closed ends of the seats of the end standards, and canvas or the like 40 wrapped about the bars.

3. In a car, tracks arranged longitudinally of the car, chairs having adjustable backs and having bases slidably engaged with the tracks whereby a front chair can be moved 45 close to a rear chair and the back of the front chair lowered to rest on the seat of the rear chair, and means for forming upper berths above the chairs, including elements removably fixed to the floor of the car out- 50 side of the tracks.

4. In a car, chairs having adjustable backs so that the back of a front chair can be moved down and rested upon the seat of a rear chair, means to slidably connect the 55 chairs to the car floor, and means removably connected to the car floor for forming berths above the chairs.

5. In a car, a separable and removable framework for forming upper berths, means 60 to removably connect same to the car floor, tracks, chairs adjustable thereon to form lower berths, and means to movably connect the chairs to the car floor so that same may

be rotated and related to form the lower berths.

65

6. In a car, standards removably connected to the car floor and having upper seats, the seats of end standards having outer end walls and the seats of intermediate standards having both of their ends open, 70 bars in the seats having their outer ends engaged with said walls, and a fabric member connecting the bars to form a bed.

7. In a car, tracks, rotatable chairs movable and adjustable thereon to conjointly 75 form a lower berth, and an open separable frame work which engages on opposite sides of the chairs and which is removably connected to the car to form an upper berth.

8. In a car, a pair of tracks, and rotatable 80 and adjustable inclining chairs having bases slideable in the tracks whereby to allow of sliding of the chairs but to prevent same from tipping, a separable frame-work adapted to inclose said chairs, and a resilient 85 fabric fastened to said frame-work.

9. In a car, two pairs of tracks with a space between the two pairs adapted to receive a table in said space, and chairs slideable in the pairs of tracks.

90

10. In a car, tracks, a lower berth formed by adjustable inclining and rotatable chairs which are mounted on said tracks, and an upper berth formed by open framework removably connected to the car.

95

11. In a car, the combination of an automobile body with means of providing upper and lower berths which comprise a plurality of lower berths consisting of inclining, rotatable and slideable chairs and tracks for said chairs and a separable frame work adapted 100 for use as upper berths.

12. In a car, the combination of an automobile body with means of providing upper and lower berths which comprise a plurality 105 of lower berths consisting of inclining, rotatable and slideable chairs, tracks for said chairs, and a separable and removable open frame-work to inclose said chairs and provide a frame-work for upper berths directly 110 over the top of the lower berths.

13. In a combined touring and sleeping car, tracks secured to the floor thereof, a plurality of inclining, rotatable and slideable 115 chairs secured to said tracks and adapted to form lower berths, open and separable frames surrounding said chairs, a resilient fabric attached to said frame-work directly over the top thereof to provide upper berths.

14. In a combined touring and sleeping car, comprising the following instrumentalities: flanged tracks, a chair slidably secured to said tracks which is arranged and adapted to provide a lower berth, an open and separable frame-work adapted to surround and 120 extend above the top of said chair, and a 125

supporting fabric connected to the framework above the lower chair berths, as described and set forth.

15. In a combined sleeping and touring car, tracks, chairs slidably secured to said tracks which are adapted to be used for lower berths, open, separable and removable

frames surrounding said chairs and a supporting means connected to said frame to provide upper berths, as described and set forth.

In testimony whereof I affix my signature.

ELI T. ZIMMERMAN.
